AERIAL PLATFORM

Emmet G. Slusher, Rte. 2, Lexington, Mo.

Filed Sept. 27, 1965, Ser. No. 87,167

Term of patent 14 years

(Cl. D14—3)

Fig.3.

Fig.2.

Fig.4.

Fig.5.

FIG. 1 is a top plan view showing the design of my aerial platform;

FIG. 2 is a side elevational view thereof;

FIG. 3 is a front end elevational view thereof;

FIG. 4 is a rear end elevational view thereof; and

FIG. 5 is a side elevational view thereof illustrating the side opposite to that shown in FIG. 2 and showing the boom and platform in their extended positions.

The dominant features of my design reside in the portions shown in full lines.

I claim:

The ornamental design for an aerial platform, as shown and described.
